VARIABLE SELECTIVITY CONTROL SYSTEM

Leland E. Thompson, Merchantville, N. J., assignor to Radio Corporation of America, a corporation of Delaware

Application April 30, 1941, Serial No. 391,166

1 Claim. (Cl. 178—44)

This invention relates to a variable selectivity control system for radio signal conveying circuits, and has for its primary object to provide an improved system for variable control of the selectivity characteristic of a signal conveying circuit over a relatively wide range.

It is also an object of this invention to provide a selectivity control system for signal conveying circuits and the like which has a selective piezoelectric filter characteristic, the degree of selectivity being variable or adjustable by simple variable resistor means without change in the crystal frequency or other circuit constants.

It is a further object of this invention to provide an improved variable selectivity control system comprising a crystal bridge network having an input and an output circuit and simple variable resistance means for varying the input or output circuit impedance for the crystal, whereby the degree of selectivity of the network may be varied or adjusted between relatively wide limits.

The invention is particularly adapted for use in connection with communications receiving systems and, in a present preferred embodiment, is adapted for use in intermediate frequency and similar signal amplifier systems.

The invention will, however, be further understood from the following description when considered in connection with the accompanying drawing, and its scope is pointed out in the appended claim.

In the drawing, Figure 1 is a schematic circuit diagram of a signal conveying system comprising an intermediate frequency amplifier circuit embodying the invention, and

Figure 2 is a graph showing curves illustrating certain of the selectivity characteristics of the circuit of Figure 1.

Referring to Figure 1, a quartz or other suitable crystal 5 is provided with a signal input circuit 6 and a signal output circuit 7 both of which are tuned and provided with a variable resistance element in shunt therewith.

In the present example, the output circuit 7 comprising an inductance winding 8 and a shunt tuning capacitor 9 is provided with a shunt variable resistor 10. The crystal output electrode 11 is connected with the high potential side 12 of the circuit 7, while the low potential terminal 13 is preferably grounded, as indicated. The circuit is variably tunable by means of a movable ferromagnetic core represented at 14 in conjunction with the inductance 8.

The input circuit 6 comprises the secondary 15 of an intermediate frequency coupling trans-

former 16 which is shunted by two series-connected capacitors 17 and 18, the midpoint 19 being connected to ground, as indicated at 20. This circuit is connected at one terminal 21 with the input electrode 22 of crystal, and, at the other terminal 23, it is connected through a neutralizing capacitor 24, with the output electrode of the crystal.

Signals are applied to the secondary 15 through 10 the primary 25 of the transformer 16, which is also provided with a shunt tuning capacitor 26, and movable ferromagnetic tuning cores represented at 27 are provided for variably adjusting the tuning of both the primary and secondary. 15 Signal input leads for intermediate frequency signals in the present case are indicated at 28.

The input circuit 6 is tuned within the intermediate frequency response band, preferably at the intermediate frequency, and provides a relatively high impedance input circuit for the crystal.

The filter circuit thus provided is made more selective or sharper by reducing the resistance across one of the tuned circuits. The lower this 25 resistance, the more constant the impedance is with various frequencies near resonance, and the selectivity finally depends upon the crystal alone, which normally provides a relatively sharp selectivity characteristic.

Therefore, by variably adjusting the shunt resistance 10 for one of the crystal circuits, such as the output circuit 7, the selectivity characteristic of the network may be varied over a relatively wide range. In receiving systems, this permits 30 the selectivity to be varied by a simple panel control knob connected with the variable resistor.

The output circuit may be coupled to further 40 amplifying stages, such as the amplifier indicated at 30, and is connected to the crystal output circuit 31 through a switch 32 providing an alternative connection 33, whereby a resistor 34 is connected across the output of crystal in place of the circuit 7.

In the present example, the input circuit 6 is 45 also provided with a variable resistance device 36 which may be connected to operate conjointly with the variable resistance 10, as indicated by the dotted connection 37. Thus, a variable resistance element may be provided in shunt with both the input and output circuits of the crystal as an improvement providing selectivity control over a wider range of variation.

Furthermore, when both resistors 10 and 36 are adjusted for maximum resistance, the cir-

cuits have a broad frequency response as indicated by the curve 40 in Figure 2. This is a desirable characteristic in the reception of voice and modulated signals, as the intelligibility is improved when the side band frequencies are attenuated to a limited degree. This circuit may be sharpened by reducing the resistance at 36 and 10, preferably jointly, as above described, to approach the crystal selectivity curve indicated at 41. This curve is also the same with the resistor 36 set at minimum value and the resistor 34 only in the output circuit.

However, with the resistor 36 maximum, the response is broadest as indicated by the curve 42, this being with the resistor 34 in the output circuit. Thus, when the switch 32 is moved to the contact 33, the resistance load 34 alone is provided on the output circuit of the crystal, while the selectivity characteristic may be varied by changing the value of the resistor 36 alone between that indicated by the curve 41 and that indicated by the curve 42. This circuit has the advantage that the input circuit 6 and the transformer connected therewith may be an ordinary intermediate frequency transformer adapted for the usual shielding. In this case, the tuned circuit 7 may be omitted, the switch 32 being closed to the contact 33, or the circuit otherwise suitably arranged to include the resistor 34 in shunt across the circuit.

It will be noted that by providing high impedance tuned circuits for both the input and output connections for the crystal, the sides of the selectivity characteristic curve 40 are more nearly vertical and the resonance width of the curve is greater than is possible with other known arrangements affording any extensive degree of selectivity variation, without changing the circuit components.

The intermediate frequency amplifier circuits of a receiving system are readily adapted for variable selectivity control by shunt resistance control means in conjunction with a crystal filter as shown and described. However, the full selectivity characteristic of the crystal filter network may be utilized and the degree of selectivity may be varied at the input and the output circuit of the filter or both in connection with other signal conveying or amplifier systems in a similar man-

5 ner. The variable selectivity control circuit may comprise a high impedance signal source or broadly tuned circuit shunt resistance controlled and feeding a neutralized crystal of the bridge type. The crystal may be coupled at the output side to a simple resistor or into a broadly tuned circuit across which a shunt variable resistance is provided for sharpening the selectivity as the resistance is decreased as in the input circuit.

10 Thus, the crystal may be preceded and followed by broadly tuned circuits, each resistance controlled.

15 The shunt resistor arrangement for controlling the selectivity affects the tuned circuits near the resonant frequency only and thus, at frequencies considerably removed from resonance, the circuits 6 and 7 drop to a low impedance, thus improving the filter characteristic.

20 This impedance arrangement in series with the series resonance of the crystal at both the input and the output circuits is made variable by simple shunt resistor means for said circuits, whereby the selectivity may be varied from relatively broad to substantially that of the crystal without changing the crystal frequency or other circuit components.

25 I claim as my invention:

30 An intermediate frequency amplifier circuit comprising, in combination, a coupling transformer having a tuned secondary responsive to a predetermined intermediate frequency, a balanced crystal bridge circuit including a crystal resonant at said frequency connected to the secondary, means providing a variable shunt resistance connection across the secondary on the input side of the crystal effectively in series with the series resonance of said crystal, an output circuit for said crystal, a tuned high impedance output circuit for said crystal responsive to the intermediate frequency comprising a variable inductance and a shunt capacitor, and means providing a variable shunt resistance connection across said last-named circuit effectively in series with the series resonance of said crystal and conjointly variable with said first-named resistance means to increase the selectivity of said network as the resistance of said means is reduced in value.

40 45 LELAND E. THOMPSON.
